UNITED STATES PATENT OFFICE.

DICKRAN M. SARKISIAN, OF FOREST HILLS, NEW YORK.

HEADING-HOOK.

1,245,515.

Specification of Letters Patent.

Patented Nov. 6, 1917.

Application filed June 26, 1915. Serial No. 36,433.

To all whom it may concern:

Be it known that I, DICKRAN M. SARKISIAN, a citizen of the United States, residing at Forest Hills, in the county of Queens and 5 State of New York, have invented certain new and useful Improvements in Heading Hooks, of which the following is a specification.

This invention relates to improvements in 10 devices known as heading hooks for effecting "French headings" or "headings" in curtains, draperies and the like. These "heading hooks" have heretofore generally consisted of a unitary wire member so bent 15 upon itself that there is provided a stem portion having means whereby the stem may be arranged vertically and sewn to a piece of such goods and that there is also provided as an extension from said stem, and in the 20 general line thereof, a hook of substantially an inverted U shape, that is, with the opening downward. The hook referred to is in practice utilized to engage with the edge of an upstanding support, with the stem portion 25 located between said support and the draped goods.

It has been found that in a device of this class wherein a terminal portion thereof is formed into an eye for receiving the stitches 30 that sew the same to the goods, the application of such stitches is of very little use for any length of time, and a constant annoyance, and damage to the goods themselves, results from the fact that, due to the upward 35 strain on the hook and stem on account of gravity, and also on account of side strain on the free leg of said hook when holding the goods, the eye quickly works free from the stitches, no matter how many such 40 stitches are employed.

The cardinal object of this invention, then, is to provide a device wherein such an occurrence can never happen, and wherein the eye is so conformed, with reference to one set 45 of stitches, and preferably with one only, that neither said one set of stitches nor the other sets of such stitches which may be engaged with portions of the eye, can ever slip from their appointed positions.

50 Such an embodiment is illustrated in the accompanying drawing, wherein Figure 1 is a side elevation thereof, and Fig. 2 is a front elevation thereof.

Similar reference characters refer to similar parts throughout the two views.

The reference numeral 3 indicates the

stem aforesaid; and the reference numeral 4 indicates the hook aforesaid, 4^a is the bend of the hook, 4^b is the free leg aforesaid, and 4^c is the leg of the hook or U that is directed 60 away from the stem. Intermediate the leg last-mentioned and said stem, there is formed an eye 5 not heretofore mentioned, and at the upper end of stem 3 there is formed an eye 6. This brings us to a description of the peculiar conformation and 65 consequent important functions of the eye, in connection with the object of the invention above specifically mentioned. In its present embodiment this eye 6 may be described as being heart shaped, that is, there is provided in the upper arc thereof a centrally down bent or inset portion, for receiving a set of stitches as shown at 7. This set of stitches, as well as the set 8, and also the 70 preferably present sets 9 and 10, are as aforesaid passed through the piece of goods or the like indicated generally at 11 in Fig. 1.

It will be seen that with the set of stitches 80 8 in place, and merely the set of stitches 7 in place, the presence of the down bent or inset portion aforesaid of the eye prevents the stitches 7 from advancing toward the opening 6^a, between the stem 3 and the end of 85 the curved part that constitutes the eye 6, and therefore from escaping from engagement with the eye 6. In this connection it should be mentioned that with these unitary bent wire "heading hooks" commercially 90 constructed by automatic machinery, the point 6^a is in almost no case found to be completely closed. With the threads 7 thus anchored fixedly on the reentrant angular 95 part of the eye 6, and with the threads 8 in place as aforesaid, the stem is anchored against thrust in any direction relatively 100 of the supported goods, and consequently the sets of threads 9 and 10 are, or either of them is, similarly anchored against displacement, because the reentrant angular portion of eye 6 is bent down in a direction opposite to the direction of the strain of gravity on the stem when the device is in use.

Preferably the wire at the inset or reentrant angular portion of eye 6 is indented or roughened, to further prevent side slippage of the threads 7.

It will be seen that the embodiment disclosed, while of simple structure, may be as 110 inexpensively manufactured, and with the consumption of practically as short a length

of the wire employed, as the usual heading hooks which lack the important inset or re-entrant angle portion.

Inasmuch as many changes could be made 5 in the above construction, and many apparently widely different embodiments of my invention could be made without departing from the scope thereof, it is intended that all matter contained in the above description or shown in the accompanying 10 drawings shall be interpreted as illustrative and not in a limiting sense.

It is also to be understood that the language used in the following claims is intended to cover all the generic and specific 15 features of the invention herein described and all statements of the scope of the invention which, as a matter of language, might be said to fall therebetween.

20 I claim:

1. In a heading hook of the class described, comprising a length of unitary material having a stem portion, a forwardly opening hook portion at one end of the 25 stem and having a portion bent into a terminal eye at the opposite end of the stem, said eye having a reentrant angular portion.

2. In a heading hook of the class described, comprising a length of unitary material having an intermediate straight stem portion and having at one end a portion bent into a terminal eye for said stem, said eye having an intermediate portion bent 30 into a reentrant angle which lies in the same plane as that which contains the eye proper and a forwardly opening hook at the opposite end of the stem.

3. In a heading hook of the class de-

scribed, comprising a length of unitary material having a portion bent into a stem 40 and having an adjacent portion bent into a terminal eye for said stem, said eye being substantially heartshaped, with the point of the heart directed toward the other end of the stem and a forwardly opening hook at 45 the opposite end of the stem.

4. In a heading hook of the class described, comprising a length of wire providing a stem portion having an upper terminal eye provided with a reentrant angular 50 portion, the other terminal of the stem being bent into an eye and thence bent backward toward the upper terminal, and then forwardly again to provide a downwardly opening hook.

5. In a heading hook of the class described, comprising a stem portion, a forwardly opening hook portion at one end of the stem, and a transverse attaching portion 55 at the other end of the stem, including an angular part, the point of which is directed toward the hook and end of the device.

6. In a heading hook of the class described, comprising a stem portion, a forwardly opening hook portion at one end of the stem, and a transverse attaching portion 60 at the other end of the stem, including an angular part, the point of which is directed toward the hook end of the device, said angular part being indented or roughened.

In testimony whereof I affix my signature in presence of two witnesses.

DICKRAN M. SARKISIAN.
